UNITED STATES PATENT OFFICE.

EDWIN R. RUUD, OF PITTSBURG, PENNSYLVANIA.

WATER-HEATER.

No. 908,007.

Specification of Letters Patent.

Patented Nov. 3, 1908.

Application filed January 6, 1900. Serial No. 478.

To all whom it may concern:

Be it known that I, EDWIN RUUD, of Pittsburgh, in the county of Allegheny and State of Pennsylvania, have invented a certain new and useful Improvement in Water-Heaters, of which improvement the following is a specification.

My present invention relates more particularly to automatic water heaters designed to heat water to be used as hot water for domestic or other purposes or to heat the water to convert the same into steam for power, heating, or other purposes. The particular form of heater herein chosen to illustrate the invention is of the general class or type which is exemplified in Letters Patent of the United States No. 610281, granted and issued to me under date of September 6, 1898, but is also applicable in other types of thermally regulated gas heating apparatus, and its object is to provide effective and reliable means whereby waste of gas, during periods in which it is not desired to heat water, may be prevented, and liability to damage to the heating appliance or its connections, by the application of heat in the absence of a proper supply of water, or by the excessive application of heat when water is not drawn off from the heater, due to the sticking of the water valve mechanism, may be effectually obviated. The inventive idea is capable of being embodied in a variety of mechanical structures, one of which, for the purpose of illustration, is shown in the accompanying drawings, but it is to be expressly understood that said drawings are designed for the purpose of illustration only and not for the purpose of defining the limits of the invention, reference being had to the claims for that purpose.

The improvement claimed is hereinafter fully set forth.

In said drawings: Figure 1 is a vertical central section through a water heater illustrating an application of my invention, and Figs. 2 and 3, similar sections through modified forms of the water supply controlling mechanism.

My invention is herein shown as applied in an automatic water heating apparatus, the water receptacle of which is in the form of a coil of pipe, 1, one of the terminals of which is connected, by an elbow, 1^a, to a water inlet pipe, 1^b, and the other to a tube, 12, which is, in turn, connected to an outlet pipe, 12^a, leading to a desired point of delivery,

such as spigot 12^b. It will be obvious that, if preferred, the tube, 12, might be interposed between two sections of the coil, 1, as in Letters Patent 610,281, aforesaid. The coil, 1, which is supported on a base or stand, 3, is heated by a main gas burner or burners, 4, ignited by the flame of an auxiliary lighting or "pilot" burner, 5, and gas is supplied to all of said burners from a service pipe 6. The pilot burner, 5, is connected directly with the service pipe, 6, by a branch supply pipe, 11, and the main burners, 4, are connected, by a branch supply pipe, 10, with a casing, 59, communicating with the service pipe, 6, and containing a gas supply valve, 60, and a gas regulating valve, 7, by which valves the supply of gas to the main burners is controlled and regulated, as presently to be described.

The water inlet pipe, 1^b, of the heater coil, 1, leads into the lower end of a valve casing, 55, to the upper end of which is connected a water supply pipe, 56, leading from a source of water supply under sufficient pressure to effect the traverse of water through the coil, 1. Communication between the pipes, 56, and 1^b, is controlled by a piston, 57, working in the casing, 55, and constantly subject to the pressure in the supply pipe, 56.

As shown in Fig. 1, the piston, 57, not only performs the function of a pressure element, but also acts, in and of itself, as a water-supply valve, when moved sufficiently downwardly by the pressure of water on its upper side, it, in such case, uncovering recesses, 58, in the bore of the casing, 55, through which water is admitted from the supply pipe, 56, to the inlet pipe, 1^b, and heater coil, 1. Said piston may, however, if preferred, be employed to actuate an independent water-supply valve, 57^a, as shown in Figs. 2 and 3, and such a construction is, under my invention, the mechanical equivalent of an integral piston and water-supply valve.

The gas service pipe, 6, leads into a chamber or casing 59, which is preferably formed integral with the casing, 55, of the water supply valve piston 57, but which may be independent thereof, and a gas supply valve, 60, seating on a partition in the casing, 59, controls communication between the gas service pipe 6, through the casing, 59, and a chamber, 7^a, connected to or forming part of said casing. A gas regulating valve, 7,

controls communication between the chamber, 7^a, and a chamber, 7^b, from which latter chamber the branch gas supply pipe, 10, leads to the main burners, 4. The piston 57, is fixed upon a rod or stem, 61, and the gas supply valve, 60, is fixed upon a stem 63, and said stems are connected, by links 64 and 65, respectively, to opposite ends of a lever, 66, which is pivoted centrally upon a suitable stand or bearing, 67. The opening movement of the water valve piston, 57, being downward, and that of the gas supply valve, 60, upward, it will be seen that said valves are so connected that their opening movements are coincident and their closing movements are also coincident. A closing spring, 62, bears upon the top of the gas supply valve, 60, said spring acting in opposition to the pressure of water upon the water valve piston, 57, and serving to seat the gas supply valve when said pressure is insufficient to overcome its tension.

Figs. 2 and 3 illustrate constructions in each of which the piston, 57, is, as in the instance first described, subject to the pressure of water in the supply pipe, 56, but instead of also acting as the water supply valve, it, in this case, actuates an independent water supply valve 57^a. As shown in Fig. 2, the valve, 57^a, is located below the piston, and controls direct communication between the water supply pipe, 56, and the interior of the valve casing, 55, to which the inlet pipe 1^b, is connected. The valve is unseated by the downward movement of the piston, 57, to which pressure from the supply pipe is imparted through a lateral passage, 55^a, on the casing, and is returned to its seat by a spring, 57^b. In the construction shown in Fig. 3, the water supply pipe 56 leads into the valve casing, between the piston, 57, and the water supply valve, 57^a, and said valve, which controls communication between the casing and the inlet pipe, 1^b, through a lateral passage, 55^b, on the casing, is unseated by the contact of a collar, 61^a, on the piston stem, 61, and is seated by a spring, 57^b, interposed between and bearing on the piston and the valve. Other structural variations, embodying the same operative principle, will readily suggest themselves to those skilled in the art, and may be made without departure from the essential features of my invention.

55 The gas regulating valve, 7, is actuated by a thermostat or thermal regulator, of any suitable and preferred construction, which, in this instance, is shown as consisting of the tube 12, which is connected to the water heater coil, 1, a tube 13, which is located within the tube, 12, and is formed of metal having a comparatively high coefficient of expansion, said inner tube, 13, being fixed at one end and free at the other, and a rod, 14, which is composed of less expandible

metal than the tube 13, and which projects at one end outside of the tubes, 12 and 13. The projecting end of the rod, 14, bears against a pivoted lever, 15, the free end of which bears against an adjustable set screw 16^a, engaging a thread in a lever, 16, which is pivoted at one end, by a pin, 16^b, to a bracket or support, 16^c. The lever, 16, bears, adjacent to its free end, against a nut, 17, which is adjustable on the stem, 18, of the gas regulating valve, 7, and a spring, 19, bears on the valve, 7, with a constant tendency to move it towards its seat, such tendency being counteracted by the contraction of the tube, 13, under reduction of temperature, which contraction, acting through the rod, 14, and the lever system upon which said rod bears, moves the gas regulating valve, 7, to a greater or less extent from its seat.

The specific form or construction of thermostat above described, which is substantially similar to that set forth in Letters Patent No. 610,281 aforesaid, is not of the essence of my present invention, and the same is equally applicable in connection with other thermal regulating mechanisms which operate to control the supply of heating medium to burners by effecting movements of a regulating valve.

Inasmuch as the function of the gas supply valve, 60, is to fully open or to completely close, as the case may be, communication between the gas service pipe, 6, and the main burners, 4, without effecting regulation or graduation of supply, while that of the gas regulating valve, 7, is to regulate or graduate the supply of gas to the main burners during the periods in which the supply valve, 60, is open, it will be seen that the relative position of said valves, 60 and 7, in the line of supply to the main burners, is immaterial. The regulating valve, 7, might, therefore, if desired, be interposed, without variation of operative principle or result, between the service pipe, 6, and the supply valve, 60, instead of, as in the instance shown, between the supply valve and the main burners.

In the operation of a water heater embodying my invention, the reduction of pressure on the outlet side of the piston, 57, resultant upon the drawing off of water from the heater at the delivery cock of the outlet pipe, 12^a, causes the piston, 57, to be moved downwardly by the higher pressure in the water supply pipe, 56, thereby uncovering the ports, 58, or unseating an independent water supply valve, 57^a, as the case may be, and admitting a supply of water to the heater coil equal to that which was withdrawn therefrom. The gas supply valve, 60, is, through its connection with the piston 57, simultaneously opened, and admits gas to the main burners, 4, at which it is ignited by

the flame of the pilot burner, 5, and, by its combustion, imparts heat to the water in the coil. So long as water continues to be drawn from the heater, the admission of water to the heater coil, and of gas to the main burners, will continue, the water valve and gas supply valve remaining open, and the supply of gas being regulated by the regulating valve, 7, as controlled by its thermostat. 5 Upon the cessation of the delivery of water from the heater, the pressure on the lower side of the piston, 57, will thereby be reinstated, and the pressure of the water in the supply pipe, 56, not being then sufficient to hold the piston 57, in position to maintain the flow of water and gas through its ports, 58, and the port governed by the gas supply valve, 60, respectively, the spring, 62, will seat the valve 60, thereby cutting off the 10 supply of gas to the main burners, 4, and, through the connections of said valve with the piston, 57, move said piston into position to cut off the flow of water to the heater coil. 15

While the specific form of the invention above described is designed more particularly for heating water to be withdrawn from the apparatus in the form of hot water, it will be at once apparent to those skilled in the art that the invention is equally applicable to the heating of water to convert it into steam for power, heating, or other purpose, in which latter event the coils would be constructed strong enough to withstand the internal pressure and the thermostat set 20 to act at any desired degree of temperature above 212° F. Moreover, it will be apparent that while gas is referred to in the foregoing description as the fuel employed, nevertheless any other suitable fuel capable of being 25 conducted to the burners by means of a suitable conduit and its flow controlled by suitable valves would be within the spirit of the invention.

My invention is of substantial advantage in practice, both in preventing waste of gas by reason of unnecessary combustion thereof at the main burners, and in guarding against damage resultant upon accidental interruption of water supply to the heater, or upon excessive application of heat, due to the sticking of the piston and the consequent unrestricted admission of gas to the main burners. If water either in the form of hot water or in the form of steam is not drawn 55 from the heater, no gas is supplied to the main burners, and there is no consumption of gas during the periods in which hot water or steam is not drawn or needed, except the comparatively small volume which is required to maintain a flame at the igniting or pilot burner. A material economy is thus effected, as compared with a heater in which the main burners are kept constantly lighted. 60 The provision of means for regulating and controlling the supply of gas to the main

burners, independently of its admission thereto by a main supply valve actuated by a water pressure piston, affords an effectual safeguard against overheating and damage to the heater and connected piping due to accidental interruption of the water supply by reason of the sticking of the piston or derangement of the water supply mechanism. The liability to failure of water supply, or to excessive heating, due to derangement or defective operation of the mechanism, and the damage resultant thereon, have heretofore been found to be serious objections to heaters in which water pressure operated gas supply valves are employed, and by the independent 70 and positive control of a regulating valve and thermostat which is provided in my invention, heaters of this type are rendered safe and reliable. It will be seen that if the piston should, from any cause, be stuck fast, 75 or otherwise rendered inoperative while the gas supply valve was open, the thermostat would immediately and automatically act upon the regulating valve, and by cutting off the supply of gas to the main burners, 80 prevent any damage to the heater coil or its connections.

I claim as my invention and desire to secure by Letters Patent:

1. In a water heater, the combination of a water receptacle having an inlet and outlet, a burner for heating the same, a fuel supply conduit leading to said burner, means actuated by the water and controlling said fuel supply, and independent means controlling 95 said fuel supply and operated by variations of temperature in the water receptacle.

2. In a water heater, the combination of a water receptacle having an inlet and outlet, a burner for heating the same, a fuel supply 100 conduit leading to said burner, a motor actuated by the water and controlling said fuel supply, and independent means controlling said fuel supply and operated by variations 105 of temperature in the water receptacle.

3. In a water heater, the combination of a water receptacle, a burner for heating the same, a water supply conduit, a fuel supply conduit, a water actuated element, a thermostat, and a plurality of independent valves 110 in the fuel supply conduit, one of said valves being controlled by said element and the other by said thermostat.

4. In a water heater, the combination of a water receptacle, a burner for heating the same, a water supply and a fuel supply, a valve operated automatically upon variations of pressure in the water of the water receptacle and controlling said fuel supply, and independent means controlling the fuel 120 supply and operated by variations of temperature in the water receptacle.

5. In a water heater, the combination of a water receptacle having an inlet and outlet, a burner for heating the same, a gas supply 125

valve controlling the supply of gas to the burner, a piston operated by unbalancing the water pressure on opposite sides thereof and actuating said gas supply valve, a regulating valve controlling the flow of gas to the burner independently of the gas supply valve, and a thermostat or thermal regulator actuating the regulating valve.

6. In a water heater, the combination of a 10 water receptacle, a burner for heating the same, a gas supply valve controlling the flow of gas to the burner, a water supply valve piston actuated by the supply of water to the water receptacle upon variations of pressure 15 therein, means through which the opening of the gas supply valve is effected by the water supply valve piston, a regulating valve controlling the flow of gas to the burner independently of said gas supply valve, and a 20 thermostat or thermal regulator actuating the regulating valve.

7. In a water heater, the combination of a 25 water receptacle, a burner for heating the same, a gas supply valve controlling the flow of gas to the burner, a water supply valve piston actuated by the supply of water to the water receptacle and upon variations of pressure therein, means through which the opening of the gas supply valve is effected. 30 by the water supply valve piston, a spring bearing on the gas supply valve and acting to effect the closure thereof and the shifting of the water supply valve piston, a regulating valve controlling the flow of gas to the 35 burner independently of the gas supply valve, and a thermostat or thermal regulator actuating the regulating valve.

8. In a water heater, the combination of a 40 water receptacle, a main burner for heating the same, a water inlet for said receptacle, a pilot burner for igniting the main burner, a gas service pipe, a branch pipe connecting the gas service pipe with the pilot burner, a 45 gas supply valve controlling communication between the gas service pipe and the main burner, a piston connected to and actuating said gas supply valve and actuated by unbalancing the water pressure within and without said receptacle, a regulating valve 50 controlling the flow of gas to the main burner independently of the gas supply valve, and a thermostat or thermal regulator actuating the regulating valve.

9. In a water heater, the combination of a 55 water receptacle having an inlet and outlet, a burner for heating the same, a fuel supply conduit leading to said burner, means actuated by the water and controlling said fuel supply, independent means controlling said fuel supply, and a thermostat in the water receptacle and in operative relation with said independent means.

10. In a water heater, the combination of a 60 water receptacle consisting of a coil having an inlet and outlet, a burner for heating the

same, a fuel supply conduit leading to said burner, means actuated by the water and controlling said fuel supply, independent means controlling said fuel supply, and a thermostat in the circuit of the coil and in 70 operative relation with said independent means.

11. In a water heater, the combination of a 75 water receptacle consisting of a coil having an inlet and outlet, a burner for heating the same, a fuel supply conduit leading to said burner, means actuated by the water and controlling said fuel supply, independent means controlling said fuel supply, and a thermostat in the outlet portion of the coil 80 and in operative relation with said independent means.

12. In a fluid heater, the combination of a 85 receptacle having a water inlet and an outlet, a burner for heating the same, a fuel supply conduit leading to said burner, means actuated by the water and controlling said fuel supply, and independent means controlling said fuel supply and operated by variations of temperature in said receptacle. 90

13. In a fluid heater, the combination of a 95 receptacle, a burner for heating the same, a water supply conduit, a fuel supply conduit, a water actuated element, a thermostat, and a plurality of independent valves in the fuel supply conduit, one of said valves being controlled by said element and the other by said thermostat.

14. The combination of a receptacle, a 100 burner for heating the same, a water supply and a fuel supply, a valve operated automatically by the water upon variations of pressure in said receptacle and controlling said fuel supply and independent means controlling the fuel supply and operated by variations of temperature in said receptacle. 105

15. The combination of a fluid receptacle, means for establishing a flow of a fluid therethrough, a burner for heating the same, a fuel supply conduit leading to said burner, 110 a valve for governing said fuel supply conduit, means actuated by the fluid while flowing for opening said valve, said valve, normally, being returned to its closed position when the flow of the fluid ceases, and independent means for controlling said fuel supply and operated by variations of temperature of the heated fluid. 115

16. In a fluid heater, the combination of a 120 receptacle, having a water inlet and an outlet, a burner for heating the same, a fuel supply valve controlling the supply of fuel to the burner, a piston operated by unbalancing the water pressure on opposite sides thereof and actuating said fuel supply valve, a regulating valve controlling the flow of fuel to the burner independently of the fuel supply valve, and a thermostat or thermal regulator actuating the regulating valve. 125

17. In a fluid heater, the combination of a 130

receptacle comprising a coil having a water inlet and an outlet, a burner for heating the same, a fuel supply conduit leading to said burner, means actuated by the water and controlling said fuel supply, independent means controlling said fuel supply, and a thermostat in the outlet from the coil and in operative relation with said independent means.

18. In a fluid heater, the combination of a receptacle, a main burner for heating the same, a water inlet for said receptacle, a pilot burner for igniting the main burner, a fuel service pipe, a branch pipe connecting the fuel service pipe with the pilot burner, a fuel

supply valve controlling the communication 15 between the fuel service pipe and the main burner, a piston connected to and actuating said fuel supply valve and actuated by unbalancing the water pressure within and without said receptacle, a regulating valve 20 controlling the flow of fuel to the main burner independently of the fuel supply valve and a thermostat or thermal regulator actuating the regulating valve.

EDWIN RUUD.
